UNITED STATES PATENT OFFICE

163,911

COMPOUND TOOL

Ernest E. Sutter, Milwaukee, Wis.

Application December 30, 1949, Serial No. 6,936

Term of patent 14 years

(Cl. D93—4.3)

To all whom it may concern:

Be it known that I, Ernest E. Sutter, a citizen of the United States, residing at Milwaukee, in the county of Milwaukee and State of Wisconsin, have invented new, original, ornamental Designs for a Compound Tool, of which the following is a specification, reference being had to the accompanying drawing, forming a part thereof.

Figure 1 is a side elevational view of a compound tool showing my new design, and

Figure 2 is an elevational view taken from the right of Figure 1.

The side opposite the side shown in Figure 1 is substantially the same as the side shown.

I claim:

The ornamental design for a compound tool as shown and described.

ERNEST E. SUTTER.
